COLLAPSIBLE BENCH

Francis J. Schmidt, Wauwatosa, Wis., assignor to
The Peter-Schmidt Corporation, Chicago, Ill.,
a corporation of Illinois

Application December 21, 1945, Serial No. 636,362

7 Claims. (Cl. 155—151)

1

This invention relates to improvements in benches and the like.

It is a primary object of the invention to provide a foldable bench for use either as a table, a seat or something to stand upon, wherein the folding legs will be held by a single combination latch and clamp both in their erected position and in their collapsed position with great security and such firmness as to be free from shaking or rattling.

Another object of the invention is to provide a bench in which there is a novel arrangement of the braces with respect to notched legs, whereby the notches of the legs are adapted, when the legs are collapsed, to receive the ends of the braces.

Still another object of the invention is the provision of a combination brace, latch and clamp effective on the braces in each of two positions thereof to hold the legs erected or collapsed.

In the drawings:

Fig. 1 is a bottom perspective of an erected bench embodying the invention.

Fig. 2 is a fragmentary detail view in bottom plan showing the combination latch and clamp.

Fig. 3 is a view in bottom perspective showing the device with the legs collapsed for convenient transportation or storage.

To the bench top 4 are hinged the end frames or legs 5, each of which is preferably notched at 6. Identical braces 7 have hinged terminal mounts 8 connecting them with the respective legs 5. At their free ends the respective braces are bent downwardly at 9 and apertured at 10. The braces have other apertures 11 intermediate their ends.

Upon the lower face of the bench top 4 there is a plate 15 which is held to the bench top by screws 16 at its corners and is provided with spaced downwardly projecting pins 17 over which the respective apertures 10, 11, of the respective braces are selectively engageable.

Midway between the pins 17, the plate 16 carries a threaded stud 18 upon which there is a wing nut 19. Pivot on the stud and subject to the thrust of the wing nut 19 is a combination latch and clamp plate 20 having on its opposite margins oppositely directed notches 21.

The relative dimensions of member 20 and the braces 7 and the spacing between pins 17 is such that when the wing nut 19 is loosened and the member 20 is swung to a position of substantial alignment with the longitudinal center line of the bench top 4, the respective braces will be free for engagement with and release from the pins 17, as best shown in Fig. 2. When either of the aper-

2

tures 10 or 11 of the respective braces is engaged over the pins, the swinging pivotal movement of latch member 20 to a position transverse respecting the bench top will secure the braces against displacement and thereupon the tightening of the wing nut 19 will effectively clamp the braces to make the entire structure rigid and rattle-free.

The downwardly tilted end portions 9 of the braces accommodate the angle necessary when 10 the legs are erected as shown in Fig. 1. When the legs are collapsed, as shown in Fig. 3, the end portions 9 of the braces are accommodated in the respective notches 6 and they do not project beyond the plane of the outer faces of the collapsed 15 legs.

Thus the entire bench may be collapsed to a thickness represented by the combined thickness of the legs and the top and the collapsed legs will not only be held securely but will be clamped by 20 the same combination latch and clamp which is used to hold them with equal security and rigidity when the legs are erected.

The resulting bench is not only strong but exceptionally stable and has a variety of uses, as 25 previously indicated.

I claim:

1. A bench comprising the combination with a top having end frames comprising legs pivoted to the lower face of the top adjacent its ends, and 30 brace means pivotally connected with the respective end frames and projecting centrally beneath the top, said top being provided on its lower face with anchorage means with which the respective brace means are selectively engageable in the respective positions of said brace means when the legs are erected and when they are folded, said anchorage means comprising a pair of spaced pins, and a latch member pivoted between said pins and notched for engagement about both of 35 said pins, the respective brace means having apertures at selected points for receiving said pins, said brace means being releasably held on the pins by said latch member.

2. A bench comprising a top and legs pivoted 45 to the top beneath the ends thereof and movable between erected positions and folded positions in which said legs are collapsed into substantial face contact with the under surface of said top, and brace straps pivotally connected 50 with the respective legs, a centrally disposed threaded stud projecting downwardly from said top, a nut upon said stud, a pivoted latch member on the stud supported by said nut and provided with marginal notches, pins fastened in 55 the top beside the stud and with which the

notched margins of the latch member are engageable upon the pivotal movement of said latch member on said stud, said braces having apertures engageable with said pins and adapted to be latched and clamped in place on said pins by the movement of said latch member with its marginal notches receiving said pins and the tightening of said nut upon said latch member whereby to transmit clamping pressure therethrough to said brace straps.

3. In a bench comprising a top and foldable legs, mechanism for releasably latching and clamping said legs in erected and folded positions, said mechanism comprising braces hinged-ly connected with the legs and provided with a plurality of apertures, pins with which selected apertures of the respective braces are engageable in the said positions of the legs, a threaded stud, said pins and stud being connected with and depending from said top in adjacent position, latch means pivoted to the stud and engageable beneath said braces to secure said braces against release from said pins, and a clamping nut upon said stud in supporting relation to said latch means, said latch means being adapted to transmit clamping pressure from said nut to said braces.

4. The combination set forth in claim 3 in which a plate applied to the bottom of the bench top carries said pins and stud.

5. In a bench of the type having a top and legs hinged thereto and braces connected to the legs for holding the legs in erected or folded positions, the combination with a threaded stud connected to and depending from the top, of a

latch plate pivoted on the stud for swinging movement between positions transverse respecting the bench and longitudinal respecting the bench, said latch plate having its opposite margins provided with notches adjacent its opposite ends and pins connected to and dependent from the top and with which the respective braces are engageable and disposed at such a radius from said stud as to be engageable beneath said braces by the notched margins of said latch plate, together with means supporting said latch plate on said stud.

6. The combination set forth in claim 5 in which said last mentioned means comprises a clamp nut.

7. The combination set forth in claim 5 in which said stud and pins are mounted on a mounting plate fixed to the top, and the supporting means last mentioned comprises a wing nut on said stud.
